United States Patent Office

Des. 195,983
Patented Aug. 13, 1963

195,983

FRY PAN COVER

Leo J. Cooper, 151 Josiah St., San Francisco, Calif.

Filed Mar. 8, 1963, Ser. No. 73,881

Term of patent 14 years

(Cl. D44—1)

FIG. 1

FIG. 2

FIGURE 1 is a side elevational view of a fry pan cover showing my new design; and FIGURE 2 is a top plan view thereof.

I claim:

The ornamental design for a fry pan cover, as shown.
